BLIND STITCH MECHANISM

Joseph F. Arver, St. Paul, Minn., assignor to Hid-stitch Company, St. Paul, Minn., a copartnership composed of Joseph F. Arver and Harold E. Ruttenberg

Application April 1, 1938, Serial No. 199,397

4 Claims. (Cl. 112—176)

This invention relates to blind-stitch mechanisms for sewing machines and comprises a device detachably connected to the presser foot bar and needle bar of a sewing machine and an improved plunger, all adapted to coordinate with the cloth feeding mechanism of a sewing machine to produce so-called blind-stitches well known in the art.

This device includes distinct and advantageous improvements over my United States patent application Ser. No. 110,469, filed Nov. 12, 1936.

As in my said previous application this device employs a horizontally reciprocating needle action and is designed for high speed machines and silent action, as hereinafter fully set forth and illustrated in the accompanying drawings, in which:

Fig. 1 is a top view of my improved blind stitcher mounted on the presser foot bar and connected with the needle bar of a sewing machine, and showing a portion of the sewing machine table at and around the cloth plate.

Fig. 2 is a front elevation of the stitcher device shown in Fig. 1 and those parts below the stitcher in longitudinal section as on line 2—2 in Fig. 1.

Fig. 3 is a left end elevation of Fig. 2. Fig. 4 is a vertical longitudinal section of my improved cloth raising and guiding plunger and Fig. 5 is a right side elevation of Fig. 4. Fig. 6 is a perspective, enlarged detail view of a piece of goods and a row of blind stitches as made by this device.

Fig. 7 is a perspective view of the footplate of my attachment, its needle retaining slide and certain associated parts on the plate, the needle positioned to start penetration of goods. Figs. 8 to 13 inclusive show in progressive order various steps or conditions in making blind stitches in a piece of goods, these views showing mainly the needle action, thread manipulation and formation of thread loops by the looping member of the device. Fig. 14 is a section of the mechanism in horizontal plane as on line 14—14 in Fig. 2 revealing mainly the link construction transmitting power from the vertical needle bar to produce horizontal reciprocating action of the needle carrier and associated stitch forming means. Fig. 15 is a modification of the central part of Fig. 2.

Referring to the drawings by reference numerals, like characters designating corresponding parts in the various views, 1 designates the table or working surface of a sewing machine head and in the left end, parts of which stitching is done in cloth 2 fed step by step rearwardly in direction of arrow 3 (Figs. 1, 3, and 7) under the

presser foot of the machine. 4 is the usual removable cloth plate of the table which in this case is of special construction.

5 (in Figs. 2 and 3) is the lower and outer end 5 part of a sewing machine head from which project downwardly the usual presser foot bar 6 and needle bar 7. My device utilizes the vertical reciprocating action of the needle bar to provide horizontal reciprocation of the needle in a plane 10 parallel to table 1 and directly over its plate 4. The needle action provides successive penetrations of cloth 2 which is fed rearwardly on the cloth plate by the usual feed bar 8 reciprocable under the cloth plate and raised in proper timing 15 to contact and move the cloth rearwardly by means of the usual feed dog (not shown) well known in the art.

Said feed bar, its timing and manipulation are well known in the art but mentioned herein for 20 the purpose of revealing their function with relation to my stitcher means. As stated the cloth feeding means may be of the usual construction but it is preferred to use in conjunction with this device the feeding mechanism fully disclosed in 25 my patent application Serial No. 110,469.

This mechanism comprises a main frame, or presser foot member, comprising an L shaped frame of which the vertical part is designated 9A securable removably as at 9B to the lower and 30 exposed end of the sewing machine presser foot bar 6 and part 9 comprises an integral base of elongated quadrangular shape normally close to and parallel with the cloth plate 4 and elongated in direction of the sewing machine head 5.

35 The sewing machine needle bar 7 is parallel to and forward of the upright 9A of the frame. Between it and the frame part 9A is positioned an L shaped oscillatable lever 10 (mounted on a pin 13) normally in position with its longer arm 40 slotted as at 10S and extending in an inclined plane traversing the vertical path of the needle bar. Said slot is slidably engaged by a cross head 11 which in turn is pivotally connected to a block 12 suitably fixed on the lower end of the needle bar 7. The right or lower and outer end of the 45 main lever is pivoted at 13 to the frame part 9A to the right of the needle bar (see Figs. 2 and 3). Below the convergence of the arms of lever 10 is 50 provided a fixed forwardly directed pin 14 pivotally engaging the left end of a horizontally directed link 21 (see Figs. 14 and 2). The right end of said link is pivotally connected at 15 to an L-shaped elongated vertical flange 16 fixed as 55 at 17A on the right hand end part of a recipro-

cable needle carrier 17 which will now be described (see Figs. 1, 2, 3, and 14).

The needle carrier may best be termed a slide and comprises an elongated quadrangular frame 17 of one piece of flat metal, reciprocable between a pair of rails 18 on the upper face of the main frame base 9, said rails in parallel relation in direction from left to right. The left of the slide has means for removably but rigidly holding a needle 19 centrally and longitudinally of the slide in its opening. Obviously the needle and its slide are reciprocable in horizontal plane from left to right and vice-versa, the point of the needle directed toward the right and traverses a quadrangular opening 20 (see Figs. 1, 7, and 14) in the base 9.

It will be understood at this point that a piece of woven material 2, to be blind-stitched is fed rearwardly under the base 9 and between it and the cloth plate by means well known in the art or the means disclosed in my allowed application specified. In Figs. 6 and 8-13 inclusive I have shown goods 2 folded upon itself to make a hem and forming a folded edge 2E which edge part it will be assumed, for illustrative purposes, is going to be blind stitched, a row of said type of stitches being shown in enlarged scale in Fig. 6.

The cloth is placed initially under the base 9 with its edge 2E extending rearwardly (see Fig. 1) and guided by the downward finger 22F of a guide plate 22 fixed on the rail 18 nearest the operator (see Figs. 1, 2, and 3) said edge 2E traversing the opening 20 of base 9 where the goods are humped or ridged upwardly in inverted V form by a vertically reciprocable plunger 23 with a tapered upper extremity of unique construction (hereinafter described) and arranged to project the goods upwardly in inverted V form and in the path of the threaded needle 19 so that the goods are penetrated at the apex of said V form in such a manner that the under side of the goods does not show the thread.

In Fig. 5 the humped up goods (on upper end of plunger) are distinctly shown and line 19L indicates the horizontal path of needle movement. The needle penetrates the goods twice, at the left and right of tapered end of the plunger, said end part of the plunger in this case having certain advantageous features of construction, as follows: 23A is a central core or stem of said plunger having a limited but continuous upwardly bearing action because of a spring 24 under it and within the bore of the plunger. Said core is tapered upwardly at its upper end to conform to the tapered shape of the end of the plunger. The top edge of the tapered tip is of course central and in the path of the needle in such position that the point of the needle will contact it lightly in a groove 23G and the needle rides said groove while reciprocating in and out of the goods at the bulge in the latter caused by the said tapered end. The importance of this feature will be more readily understood hereinafter in conjunction with the description of the process in making blind stitches. The timing and vertical action of the plunger is identical with the means used in my previous application it being readily seen that the humping of the goods for needle penetration takes place while the cloth is held stationary between the base 9 and a cloth plate 4 and movement of the goods rearwardly takes place only when the needle has been drawn out (to the left) clear of the cloth.

In Figs. 1, 7, and 14, 26 designates an aperture in the left end cross member of needle carrier 17

through which extends downwardly under tension, a thread 25 (from any suitable source of supply as provided for on sewing machines) said thread under continuous light tension and below said aperture extending alongside the rear side of the needle to its eye through which the thread extends horizontally forward, or toward the operator's side of the machine, from whence the free thread end is designated 25E (see Fig. 7).

10 2H designates the humped part of the goods being stitched, whether said goods be single, multiple thickness or hemmed. To the right side of aperture 20 the base 9 is sloped or beveled to the right to bear down on the cloth as at 27 (in Figs. 5 and 14) in conformity with the slope of the right side of the tapered upper end of the plunger.

28 is a transversely directed thread guide secured parallel to the rear rail 18 and comprising mainly an arm extending over and across the needle slide, said latter arm having a notch 28N (Fig. 1) at its right side through which the feed-in thread is guided to the aperture 26.

20 In Figs. 1, 2, 7, and 9 to 14 inclusive, 29 designates a flat metal plate member in vertical plane, elongated horizontally and pivotally retained at its right hand end as on a pin 30 in front of the vertical arm of bracket 16. The left end of said member is formed with a downward offset and curved finger 29F tapered toward the left and its point directed upwardly, said point oscillatable vertically and horizontally with its point moving vertically into and out of a position alongside of the needle. This finger member will hereinafter be called the looper.

25 35 Intermediate the ends of said looper is fixed a forwardly projecting pin 31 which may comprise a roller riding the humped up edge or cam face 32F of a vertically disposed plate 32 fixed as at 33 on the front rail 18. Said cam member is distinctly shown in Figs. 1, 2, 3, and 7 in full lines, and in Figs. 8 to 13 inclusive the cam face 32F is shown dotted only, to more clearly reveal the function of the looper, it being understood that said cam face is parallel to and adjacent the front side of the looper.

40 45 At this point the mechanical action of my device up to the stitch forming needle action is as follows: The vertical reciprocating movement of needle bar 1, through cross head 11 engaging in angular slot 10S imparts silent oscillating movement to the main lever 10. This in turn, through link 21 and bracket 16 (fixed on needle carrier) imparts horizontal reciprocating movement to the needle carrier and needle 19 derives necessary stroke for penetration of cloth humped upwardly in its path and in the aperture 20 of base 9.

50 55 The reciprocating movement of bracket 16 carrying the looper gives the latter corresponding movement from left to right and vice versa, which movement causes the looper to ride on and over the cam face and consequently the free (finger) end of the looper is raised and lowered accordingly within vertical limits while traveling horizontally, said raising and lowering of finger 29F providing certain thread engaging and disengaging actions which form thread loops on top of the cloth between each cloth penetrating action of the needle, the finger action and needle action co-ordinated or timed for the purpose, as will now be described.

60 65 70 Referring particularly to Figs. 7 to 13 inclusive, Fig. 7 is a perspective view of the stitching means particularly (omitting the parts providing reciprocating action of the needle carrier) and showing the needle carrier frame in extreme left position

and the needle threaded to start stitching action its first movement being of course to the right, the needle at this time positioned with its point in spaced relation to where it will enter the cloth as at 34 in Fig. 8, 35 designating where it will emerge from the goods.

When the needle is threaded as in Figs. 7 and 8, the looper 29 is at the extreme left position with its finger 29F down parallel to and alongside of the pointed end of the needle. At this time the cloth is pressed between base 9 and the cloth plate 4 and humped in aperture 20 in the path of the needle.

Downward action of needle bar through the link means described imparts movement of the needle carrier to the right, the needle penetrating the cloth as shown in Fig. 9, two bights of thread being drawn through the goods. When the needle reaches this extreme right position the looper has ridden over the hump of cam face 32F and its finger is again positioned alongside of the exposed needle point in such position that when the needle starts to move back (to left) the tip of finger 29F enters upwardly between the adjacent bight of the thread (to the left of the needle eye) and the needle. At this time the looper is starting to rise on the cam face 32F and the finger 29F carries the thread and draws it upwardly in the form of an elongated loop designated 25L in Fig. 10. Fig. 11 illustrates the needle emerging (toward the left) out of the cloth, looper 29 coming down on the left slope of the cam face still drawing out and enlarging the loop 25L and bearing said loop toward the upper face of the cloth.

As soon as the needle is completely free of the cloth the feed bar 8 of the sewing machine functions to move the goods rearwardly one step (as from A to B in Fig. 12). The looper, still holding the thread on its finger causes the thread to be drawn out into an elongated loop 25L (Fig. 12) and as the needle reaches its extreme left position the finger brings the thread loop down on and over the cloth in such manner that when the needle again goes into penetrating action it goes through the loop 25L (see Fig. 13).

In receding from the cloth, thread extends from the aperture where the needle first entered to the front side of the needle eye, this part of the thread designated 25E in Fig. 12 becoming a single strand extending from said first point of entry to the second point of entry and lies on the lower part of loop 25L when the needle makes each succeeding penetration.

In Fig. 13 the needle is shown making second penetration as the looper finger 29F moves to right and the loop rides off the point of the finger as the latter moves downwardly to the right to assume the next pre-loop forming position shown in Fig. 9.

In Figs. 1, 7, and 14, 36 is a plate fixed on the front rail 18 and having a tapered arm 36F within opening 20 and pointed rearwardly therein. The looper finger rides over this finger both ways and the needle reciprocates under it. The main purpose of this finger is to engage and guide the thread forming each loop 25L and prevents undue jumping or misplacement of the thread while stitching as above described. The shape of said member 36 and its finger 36F may be varied considerably.

An important feature of my invention is the dual action of the plunger 23. With the construction of the main body of the plunger as in my previous application it bears upwardly yield-

ably. As shown in Fig. 5 one shoulder (to the left of the tapered tip) bears upwardly toward under side of the presser foot. This shoulder and the top edge of the plunger are simultaneously positioned vertically in transverse relation to the path of the needle according to the thickness of the cloth. The yieldable part of the plunger has previously been described. Obviously the various thicknesses of cloth modifies the vertical position of the presser foot. The plunger is reciprocated preferably by a roller actuated by the feed bar 8 of the sewing machine (Fig. 8) in coordinated timing relative to the latter as set forth in my previous application. The modification Fig. 15 reveals in place of lever 10, a beam lever 70, pivoted on pin 13, the upper end of said lever connected by means of a link 71 to the block 12 of the needle bar. The lower end of said lever 70 is pivotally connected to the left end of the link 21, at 14. The dotted lowermost position of block 12 and corresponding position of link 71 moves the needle carriage to extreme right position. The full line showing of the parts just described shows the extreme left position of the carriage, the latter being when the needle is fully retracted or clear of the goods. In other words this modified construction embodies simply a plain beam lever 70 with positive link connection to the needle bar 7 and direct connection to the link member 21 of the carriage. A beam lever and link are substituted for the L-shaped lever 10. There is no sliding contact as in slot 10S but a positive silent link motion which has proven highly efficient particularly for high speed machines.

I claim:

1. A blind stitch attachment for sewing machines and comprising a main frame of L shape in cross section the upright arm thereof detachably securable to the presser foot bar of a sewing machine, the base thereof comprising an elongated horizontal plate longitudinal of the sewing machine head, a needle holding frame retained for reciprocable movement on said base with the needle pointed toward the center of the base, an L shaped lever pivotally mounted on said arm and means connecting an arm thereof with the needle bar of the machine to impart vertical oscillating movement to said lever, the lever pivoted at the extremity of the other arm, means intermediate said L lever and the needle frame to impart horizontal reciprocating movement of the latter, said presser foot base provided with a central aperture traversed by the needle during reciprocating action, said base positioned directly over the cloth plate of the sewing machine and adaptable to bear down on cloth fed rearwardly between the base and said cloth plate, means coordinated mechanically with the cloth feeding means of the sewing machine for humping the cloth upwardly in the path of the needle in an inverted V form to provide double penetration of the goods by the needle projected horizontally through said V formation of the cloth and means for regulating the extent of said upward projection of the cloth humping means.
2. The structure specified in claim 1 and means for longitudinal guidance of the needle frame comprising a pair of fixed guide rails on the base of the presser foot member, said needle holder comprising an elongated open frame closed at the left end and carrying means for removably retaining a needle in parallel relation to and between said guide rails and pointed toward the

right end of the frame, the right end of said frame likewise closed and comprising a flat plate, elongated bracket of L shape in cross section and mounted on said latter plate, said means for imparting horizontal reciprocating movement to the needle frame comprising a pivot pin intermediate the ends of the L shaped primary lever, a vertically disposed link connecting said pivot pin and its opposite end pivotally connected to the upright arm of the said bracket fixed on the needle frame.

3. The structure specified in claim 1, and a tapered finger member secured on the base of the presser foot, the finger part thereof projecting rearwardly in the said central aperture over the cloth and comprising a thread loop retaining member and spreader.

4. A blind stitch mechanism for sewing machines having a vertically reciprocable presser foot bar, a vertically reciprocable needle bar, a cloth plate and table in common plane therebelow, a reciprocable feed bar and means actuated thereby to contact and feed the cloth rearwardly under the needle bar, the action of said feed bar synchronized with relation to the needle bar; said mechanism comprising a presser foot member of L-shape and removably fixed on the

presser foot bar with its vertical arm, its lower part comprising a flat foot piece elongated in direction transversely of the cloth movement, a needle carrying frame reciprocably retained on said foot piece and removably retaining a needle therein in horizontal plane with its point directed toward the center of the frame, means intermediate the needle bar and said needle frame for imparting horizontal reciprocating movement to the needle and its frame, said foot piece provided with an aperture in its central part and traversed by the needle, a vertically reciprocable plunger mounted under the cloth plate and having an upwardly tapering end part terminating in a diametrical edge to engage cloth fed under the presser foot and to press it upwardly in inverted V-form, in the path of the needle, to provide for double penetration of the cloth, said plunger formed with a vertically spring actuated central, reciprocable core bearing upwardly, said core formed at its upper end with a tapered terminus grooved transversely at its center for light, initial contact of the needle point and yieldable during subsequent movement of the needle in its reciprocating stitching action.

JOSEPH F. ARVER.
